UNITED STATES PATENT OFFICE.

EDWARD J. WAELEY, OF ALLEGHENY, PENNSYLVANIA.

DESIGN FOR A RAILROAD-RAIL.

SPECIFICATION forming part of Design No. 30,911, dated May 30, 1899.

Application filed May 8, 1899. Serial No. 716,025. Term of patent 7 years.

To all whom it may concern:

Be it known that I, EDWARD J. WAELEY, a citizen of the United States of America, residing at Allegheny, in the county of Allegheny and State of Pennsylvania, have invented a certain new and useful Design for Railroad-Rails, of which the following is a specification, reference being had therein to the accompanying drawing.

10 This invention relates to a certain new and original design in railroad-rails.

In the accompanying drawing I have illustrated my design by showing a perspective view thereof.

15 The leading feature of my design consists in the ends of the rail, at which point the one end of the tread 1 and the one end of the base 2 are on an even plane, while the web

3 between these two members is swelled outwardly to form a projecting knob 4, in outline resembling a part of an ellipse. At the other end of the rail the end of the tread 1 and the end of the base 2 are also upon an even plane, while the web 3 is recessed correspondingly in outline to the projecting knob 4.

Having fully described my invention, what I claim is—

The design for a railroad - rail as herein shown and described.

In testimony whereof I affix my signature 30 in the presence of two witnesses.

EDWARD J. WAELEY.
